CLAIM

The ornamental design for a bottle for a device to wash nasal passages, as shown and described.

DESCRIPTION

FIG. 1 is a perspective view of a bottle for a device to wash nasal passages showing our new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof; and,

FIG. 7 is a rear elevational view thereof.

The broken lines shown in FIGS. 1–7 are included for the purpose of illustrating environmental elements only and form no part of the claimed design.
